DESIGN FOR A COMBINED BILLFOLD, PURSE, AND MEMORANDUM PAD HOLDER

Howard A. Bauman, West Bend, Wis., assignor to Enger-Kress Company, West Bend, Wis., a corporation of Wisconsin

Application September 20, 1947, Serial No. 141,506

Term of patent 3½ years

(Cl. D87—3)

To all whom it may concern:

Be it known that I, Howard A. Bauman, a citizen of the United States, residing at West Bend, in the county of Washington and State of Wisconsin, have invented a new, original, and ornamental Design for a Combined Billfold, Purse and Memorandum Pad Holder, of which the following is a specification, reference being had to the accompanying drawing, forming part thereof.

Fig. 1 is a view in front perspective of my combined billfold, purse and memorandum pad holder, as it appears when closed.

Fig. 2 is a view in rear perspective of the article, shown in Fig. 1.

Fig. 3 is a view in perspective of my combined billfold, purse and memorandum pad holder as the same appears when unfolded.

Fig. 4 is a view similar to Fig. 3 showing the parts unfolded and open, the whole showing my new design.

I claim:

The ornamental design for a combined billfold, purse, and memorandum pad holder, as shown.

HOWARD A. BAUMAN.
